UNITED STATES PATENT OFFICE.

CHARLES TURNER, OF CHICAGO, ILLINOIS.

HEATER FOR RAILWAY-CARS.

SPECIFICATION forming part of Letters Patent No. 340,258, dated April 20, 1886.

Application filed October 15, 1884. Serial No. 145,607. (No model.)

To all whom it may concern:

Be it known that I, CHARLES TURNER, a citizen of the United States, residing at Chicago, in the county of Cook and State of Illinois, have invented certain new and useful Improvements in Heaters for Railway-Cars, which are fully set forth in the following specification, reference being had to the accompanying drawings, in which—

10 Figure 1 is a side elevation of a locomotive and that portion of my device which is attached thereto; Fig. 2, a side elevation of a car having my devices applied thereto, a portion of the side being broken away to show the 15 construction; Fig. 3, a plan section on the line $\alpha\alpha$ of Fig. 1; Fig. 4, a plan section on the line $\gamma\gamma$ of Fig. 2; Fig. 5, an enlarged view of a portion of the same; and Fig. 6, an enlarged elevation of the shield, portions of one side 20 being broken away to show the interior.

Like letters refer to like parts in all the figures.

My invention relates to ventilating devices to be applied to railway-cars, its object being 25 to furnish a full supply of fresh pure air free from smoke, cinders, and dust, the air so supplied being heated in cold weather; and to that end my invention consists in certain novel features, which I will now proceed to 30 describe, and then particularly point out in the claims.

In the drawings, A represents a locomotive of ordinary construction, above the steam-chest α of which are attached funnels B, suitably 35 connected to the forward end of the main air-supply pipe C. By reason of this location of the funnels B a constant supply of air is forced into them by the motion of the train, and so through the pipe C, from which it is distributed, as hereinafter described. Moreover, 40 the mouth of the funnels being in advance of the smoke-stack, the smoke and cinders from the stack cannot enter, nor can the dust caused by the train, thereby insuring the purity of the air-supply. The air-supply pipe C is of 45 iron or other suitable material, and a section of it is secured under each car C', and also under the tender and to the locomotive, being shown in Fig. 1 as attached immediately under the foot-board b, so that it will be out of 50 the way and protected from injury.

Suitable flexible connections are employed

between the sections on the cars, tender, and locomotive, as hereinafter described. That section of the supply-pipe C attached to the locomotive is shown as in duplicate, one part being on each side and the two parts joining at the rear. The section of pipe C under each car C' is provided with a stop-cock, c, at each end, so that the rear end of the last section of pipe may be closed to prevent the air from passing straight out through the rear end of pipe C without entering the car at all. Near each end of the car the pipe C is provided with a branch pipe, D, entering the interior of the car, being shown 65 in Fig. 2 as passing up through the floor and having a stop-cock, d, by which the flow of air can be regulated or entirely stopped. If in cold weather the outer air were allowed direct access to the interior of the car, it would 70 reduce the temperature too much. I overcome this difficulty as follows: In Figs. 2 and 4 E represents a stove or heater, such as is usually employed in passenger-cars, there being either one at one end of the car only, or, 75 as is more usual, one at each end. E' indicates a screen arranged between the car-wall and stove, to protect the former from the heat. For use in conjunction with my apparatus, I make this screen, which is of sheet-iron or other suitable material, hollow, as shown in detail in Figs. 5 and 6, and arrange inside of the same partitions e, attached alternately to the top and bottom of the hollow screen and extending not quite all the distance from top to 80 bottom. The branch-pipe D communicates with the interior of the shield at the side thereof farthest from the car-door, and the air entering through the branch pipe passes through the interior of the screen in the manner indicated by the arrows in Fig. 6, and then out through the nozzle or outlet-pipe F into the interior of the car. In its passage through the screen E' the air becomes warmed to a proper 85 temperature, so as not to chill the interior of the car, and at the same time it reduces the temperature of the screen by absorbing its heat, thereby rendering it a more efficient protection to the wood-work of the car. Owing to the position of the outlet-pipe F near the 90 door, any cold air admitted by the necessary opening of the same will receive such an admixture of warm air as will raise its temperature 95 as soon as it enters the car. At the same 100

time the outlet-pipe is so located as to be as far as possible from any of the seats, so as not to expose the passengers to a disagreeable current of air. The outlet-pipe may be provided 5 with a cock, *f*, to regulate the flow of air and the rate of its passage through the screen. Of course in warm weather, when the heater is not in use, the air may still pass through the screen, though of course without becoming 10 heated. The screen in this case, as indeed in the other, deprives the air of any cinders or the like which may accidentally have entered the pipe *C*.

The various fixed sections of the pipe *C* are 15 connected by flexible pipes. This is accomplished by attaching to each end of each section, except of course that attached to the locomotive, a flexible tube, *G*, of rubber or other suitable material. In order to allow extra 20 play I slip this tube over the end of pipe *C*, and attach to it one end of a spring, *g*, coiled around pipe *C*, and having its other end attached thereto. By this means, when any strain comes upon the tube *G*, it will slide upon 25 pipe *C*, and when the strain is removed the spring *g* will return it to its normal position.

From the above description the operation of my device will be readily understood.

It is obvious that many mechanical modifications in the construction may be made without departing from the principle of my invention, and I therefore do not wish to be understood as limiting myself strictly to the precise details of construction shown and described.

Having thus described my invention, what I claim as new, and desire to secure by Letters Patent, is—

1. In a car-ventilator, the combination, with

the funnels *B*, arranged as specified, of the pipe *C*, having its several sections connected by 40 flexible tubing, and provided with branch pipe *D*, hollow screen *E'*, connected therewith and having an outlet-pipe, and heater *E*, substantially as and for the purposes specified.

2. In a car-ventilator, the combination, with 45 the main air-supply pipe *C*, of hollow screen *E'*, connected thereto by a branch pipe, *D*, and having an outlet-pipe, *F*, the said screen having the partitions *e*, extending alternately from the top and bottom almost to the opposite end 50 of the screen, and heater *E*, substantially as and for the purposes specified.

3. In a car-ventilator, the combination, with car *C'* and heater *E*, arranged therein in one corner thereof, of hollow screen *E'*, partly surrounding said heater and having a branch pipe, *D*, at the side thereof farthest from the car-door, and communicating with the supply-pipe *C*, and an outlet-pipe, *F*, at the side nearest the car-door, substantially as and for the 60 purposes specified.

4. In a car-ventilator, the combination, with supply-pipe *C*, having a stop-cock, *c*, at each end of the car, of hollow screen *E'*, branch pipe *D*, connecting the two and having a stop-cock, *d*, and outlet-pipe *F*, having stop-cock *f*, substantially as and for the purposes specified. 65

5. In a car-ventilator, the combination, with the locomotive *A*, of the funnels *B*, arranged as specified, and supply-pipe sections *C*, arranged immediately under the foot-boards *b*, substantially as and for the purposes set forth. 70

CHARLES TURNER.
